VENETIAN BLIND AND HARDWARE
THEREFOR

Allen E. Latham, Oakland, Calif.

Application December 27, 1933, Serial No. 704,681

16 Claims. (Cl. 156—17)

This invention relates generally to Venetian blinds and the hardware therefor and more particularly to certain improvements in construction thereof which enable a better blind to be produced at less cost.

In order to obtain the most satisfactory results with blinds, it is necessary that the slats be accurately adjusted both as to tilt as well as height. As objects of the invention are included the provision of and certain improvements in blind tilting mechanisms as well as in the mechanisms for holding the cords for adjusting the tilting mechanisms and the height of the bottom rail.

It frequently happens that blinds are installed, by unskilled or careless mechanics, so that the slats rub and drag over the adjacent window frame. A construction herein disclosed prevents such an installation by requiring that the blind be installed so as to clear the window if it is not of an unusual construction.

With long blinds or very wide blinds, it is frequently necessary to include means for supporting the tilt rail at one or more intermediate points. While such means are not broadly new, being disclosed in Patent 1,793,943 of February 24th, 1931 to Leeper, the means herein disclosed includes various features of advantage not found in the prior art. Thus, the intermediate support means can be readily engaged and disengaged by a hooking action operable with the fingers while the tilt rail, and its other mechanisms, are so arranged that when the intermediate support is released the tilt rail and all the slats can be readily removed from support on the header.

The invention is also concerned with an improved means for retaining the bottom rail in a height adjusted position by means of the cords which serve to raise and lower the bottom rail to uncover and cover the window.

The invention includes other features of advantage, other objects and novel mechanisms and combination which will appear at length in the following wherein a present preferred form of construction is disclosed in connection with the drawings.

Figure 1 is a front elevation of a Venetian blind in a window opening supported by brackets, and including actuating and locking mechanisms of the present invention.

Figure 2 is a front elevation of a bracket and actuator for the tilt rail.

Figure 3 is a side elevation of the mechanism in Figure 2, a portion being in section.

Figure 4 is a section on the line 4—4 of Figure 3.

Figures 5 and 6 are respectively plan and side views showing the intermediate tilt rail support.

Figure 7 is a plan of a cord pulley construction.

Figure 8 is a section through the header rail showing the mounting of the locking mechanism for the cords for raising and lowering the bottom rail.

Figure 9 is a section on the line 9—9 of Figure 8.

Figure 10 is a side elevation for a bracket for mounting the header rail.

The Venetian, or louvre blind shown in Figure 1, includes a header rail 21, a tilt rail 22, a plurality of slats 23 and a bottom rail 24 supported by tapes 26 from the tilt rail and by cords 27 and 28 from the header rail. The tape connections enable the slats to be tilted, upon tilting of the tilt rail, as well as to be raised and lowered by cords 27 and 28 to cover to different degrees the adjacent window opening defined by frame 29.

The tilt rail is supported at its right hand end by a bracket 31, secured to the head rail, and which includes an aperture to pass a headless pin or screw 32 extending from tilt rail. At its left hand end the tilt rail is secured to a member 33 which includes an angular portion 34 having gear teeth formed thereon. A washer 36 is riveted to the angular portion (Figure 4) and is threaded to receive a screw 37 which extends from a bracket 38 so that the tilt rail is rotatably mounted at its opposite ends. When it is desired to drop the tilt rail, it is only necessary to hold the rail and release the screw 37 whereupon the left end of the rail can be dropped slightly and the screw or pin 32 drawn out of the bracket 31.

When many slats are included, or the tilt rail is very long, one or more intermediate supports are desirable. In Figures 1, 5, and 6, I have shown a heavy stiff wire 41, looped about the tilt rail and secured by a plate 42. It is to be noted that the wire loop can be rocked in the plate along the longitudinal axis of the rail so as to free it from engagement with hook extension 43 of a member 44 secured to the header. The tilt rail is sufficiently flexible to permit of a slight deflection, if this is necessary, so that the wire can be inserted and removed from the hook which ordinarily prevents accidental disengagement of the wire while supporting it during rotation of the tilt rail. The combination of the

end brackets and intermediate support means enables the blind structure to be readily removed and inserted in the header.

To rock the tilt rail a worm 46 is mounted 5 on a shaft 47 carried in bearings 48 on the bracket 38. This worm is above the gear tooth portion to facilitate assembly and removal. The shaft is rotated by a V-pulley 49 over which a cord 50 is extended. Slipping of the cord on 10 the pulley to an undesirable degree is prevented by forcing a portion of the cord against the V-face of the pulley. To accomplish this, two grooved wheels 51 are mounted on pins 52 extending between opposite sides of the pulley between 15 the adjacent inside faces of a U-member 53. Although the U-member can be supported from the head rail, in the present instance I have shown it with a leg 54 rotatably supported by a pin 56 and spaced by a washer 57 from the bracket 38.

A pull on the left hand end of the cord forces the left hand pulley to the left and rocks the U-member to the left about pin 56. This movement causes member 53 to rock about pin 56 to 25 the left, in the direction of movement of the pulley in this case. This forces the right hand pulley to press the cord into the smooth V of the pulley to wrap the cord on the pulley, thereby obviating slipping. The greater the pull on 30 the cord, the greater is the force on the opposite wheel, tending to force the cord against the pulley so that little slipping occurs, if any. While mechanisms of a similar general purpose have been used heretofore, the present device does 35 not wear or tear the cord and operates even though the cords vary in size (see Anderson patent of October 27, 1931, No. 1,829,718).

To limit the tilt of the tilt rail and prevent 40 overrunning, the teeth formed on the angular portion 34 include a half tooth 60 at each end of the gear segment. Since these will not run in the worm, a simple but effective tilt limit stop is provided.

The head rail 21 is supported (Figure 10) by 45 bracket 61 at each end thereof. These include a flange 62 from which extends a back portion 63 and two ears 64 for supporting the head rail. A screw 66 is extended into the head rail through one ear while an ear 67 on the back portion 50 extends over the head rail to prevent it tipping off the bracket. The bracket can be secured by screws 68 in the flange or in the back portion.

It is to be noted that the head rail is mounted 55 on the bracket so that the tilt rail and slats, as appear in dotted lines in Figure 10, will clear the adjacent window frame and do not drag thereover. This is accomplished by providing slot 69 therein to the left of the head rail, the center of the slot usually being over the center 60 of the tilt rail and the slats. In this way even an inexperienced, or unskilled mechanic cannot install the blind so as to drag over any usual window.

The cords 27 and 28, which support the bottom rail, run through holes in each slot, the tilt rail and the head rail. In the head rail they run down slot 69 after passing over guide pulleys 71. To facilitate construction and provide a long life blind, the pulleys are mounted on a pin 72 carried in a strap member 73 bent in a U-shape to receive the pulley and for insertion into hole 74 in the head rail through which the cord passes. The member 73 is cut away as at 76 to pass the cord.

75 Heretofore the usual practice has been to guide

the cords 27 and 28 away from head rail so that they could be freely operated to raise and lower the bottom rail, the cords being wound about a fixed support to hold the bottom rail in a desired position. In accordance with this 5 invention, semi-automatic means are provided for holding the ends 27 and 28 upon manipulation and release by an operator. A cage 81 is mounted in an angular cut in the head rail so that the ends lead off over a pulley 82 from slot 10 69, to the operator. This pulley is rotatable on a pin carried in a member 83. This member, shown as a U-member with the pulley mounted between the legs, is carried in the cage by pin 84 and has two extending arms. It is to be 15 noted that when the angle of the end passing over the pulley is varied, the member 83 moves on pin 84; in the preferred form, the member moves to a position midway between cord positions 86 and 87 in Figure 9. This movement, although 20 small, is amplified by the extending arms which extend into slots 88 in opposite legs 89 of a member carried on pin 92. The legs 89 are connected by a portion 91 which is roughened and is adjacent the inner face of the cage. 25

In operation, the portion 91 lies against the cords when the bottom rail has been adjusted and the weight of the suspended slats and rails, together with the cam contour of portion 91, hold the cord jammed against the inner face 30 of the cage. When a downward pull on the cords occurs, the jam is released and the cords run freely. When the bottom rail has been moved to a desired position, the operator merely moves the cords slightly to the left in Figures 1 and 35 9 and releases the cords. The movement to the left results in the pulley moving member 83 and in turn the portion 91 to the left to engage and jam the cords. The cords remain in this position until released by a downward pull on their 40 free ends when the device can again be manipulated after the bottom rail has been moved as desired.

I claim:

1. In combination, a Venetian blind tilt rail, a 45 header rail, a bracket secured adjacent an end of said header rail, an insertable and removable pin engaging said bracket and said tilt rail, a supporting bracket secured to said header adjacent the other end thereof and including a rotatable worm, a plate member for engaging the tilt rail to support the same, said member including a gear for engagement with said worm, and a removable member for securing said plate member on said bracket with said gear in engagement with said worm, so that said tilt rail is supported and can be moved upon rotation of said worm.

2. In combination, a Venetian blind tilt rail, a header rail, a bracket secured adjacent an end 60 of said header rail, an insertable and removable pin engaging said bracket and said tilt rail, means for supporting said tilt rail at an intermediate point from said header rail including a member movable with said tilt rail to support 65 said rail and along the longitudinal axis of said rail to release said support, a supporting bracket secured to said header adjacent the other end thereof and including a rotatable worm, a plate member for engaging the tilt rail including a gear 70 for engagement with said worm, and a member for securing said plate member on said bracket with said gear in engagement with said worm so that said tilt rail is moved upon rotation of said worm.

3. In combination with a bracket for supporting a Venetian blind tilt rail, a worm rotatable in said bracket, a pulley for rotating said worm, a cord looped around said pulley with ends thereof extending in the same direction, and means rotatable in the same direction of rotation and with said pulley for holding said cord frictionally against said pulley. 5
4. In combination with a bracket for supporting a Venetian blind tilt rail, a worm rotatable in said bracket, a pulley for rotating said worm, a cord looped around said pulley with ends thereof extending in the same direction, and two members engaging said cord, each member engaging 10 said cord as it separates from the pulley loop to retain said cord looped about said pulley. 15
5. In combination with a bracket for supporting a Venetian blind tilt rail, a worm rotatable in said bracket, a pulley for rotating said worm, a cord looped around said pulley with ends thereof extending in the same direction, two members engaging said cord, each member engaging said cord as it separates from the pulley loop to retain said cord looped about said pulley, and means for supporting said members for movement to bind said cord frictionally against said pulley upon rotation of said pulley. 20
6. In combination with a bracket for supporting a Venetian blind tilt rail, a worm rotatable in said bracket, a pulley for rotating said worm, a cord looped around said pulley with ends thereof extending in the same direction, two members engaging said cord, each member engaging said cord as it separates from the pulley loop to retain 25 said cord looped about said pulley, and means rotatable in the same direction as said pulley for supporting said members to bind said cord frictionally against said pulley upon rotation of said pulley. 30
7. In combination with a bracket for supporting a Venetian blind tilt rail, a worm rotatable in said bracket, a pulley for rotating said worm, a cord looped around said pulley with ends thereof extending in the same direction, two members engaging said cord, each member engaging said cord as it separates from the pulley loop to retain 35 said cord looped about said pulley, a plate carrying said members, and a pin supporting said plate for rotation relative to said bracket. 40
8. A Venetian blind tilt rail, a header rail, a wire looped about the tilt rail, means on said header rail for engaging said wire, and means on said tilt rail for securing said wire thereto for movement with said tilt rail and for movement 45 relative to said tilt rail to permit disengagement from said engaging means on said header. 50
9. In a Venetian blind, a head rail, a tilt rail, a bracket on said head rail, a worm on said bracket, a plate including an integral arm thereon for supporting an end of said tilt rail, a gear segment formed on said plate and engaging said worm to rock said tilt rail, and a removable spindle supporting said plate for rotation on said bracket. 55
10. In a Venetian blind, a head rail, a tilt rail, a bracket on said head rail, a worm on said bracket. 60
- et, and a plate supported from said bracket and supporting an end of said tilt rail, a gear segment formed on said plate and engaging said worm to rock said tilt rail, and a half tooth formed at each end of said segment to limit rocking of said tilt rail. 5
11. In combination, a header rail, a tilt rail, a bracket at one end of said header rail, a pin extending from said tilt rail to engage said bracket, a bracket at the other end of said head rail, a plate member supporting said tilt rail, a removable stud for supporting said plate member on said bracket for rotation, a gear formed on said plate member, and a worm for engaging said gear. 10
12. In combination, a header rail, a tilt rail, a bracket at one end of said header rail, a pin extending from said tilt rail to engage said bracket, a member looped over an intermediate portion of said tilt rail, a member supported on said head rail and extending therefrom to beneath said looped member to support said member and said tilt rail, a bracket at the other end of said head rail, a plate member supporting said tilt rail, a removable stud for supporting said plate member on said bracket for rotation, a gear formed on said plate member, and a worm for engaging said gear, said looped member being rotatable on said tilt rail to engage and disengage 15 said support member. 20
13. In combination, a pulley, a cord looped around said pulley with the ends thereof extending in the same direction, and means rotatable with said pulley for holding said cord against said pulley. 25
14. In combination, a cord, a pulley having a face over which said cord runs to move with said pulley, said cord being looped about said face with the ends of said cord extending in the same direction, a plurality of spaced pulleys, each of said spaced pulleys engaging said cord to hold said cord against said pulley face. 30
15. In combination, a cord, a pulley having a face over which said cord runs to move with said pulley, said cord being looped about said face with the ends of said cord extending in the same direction, a plurality of spaced pulleys, each of said spaced pulleys engaging said cord to hold said cord against said pulley face, and means supporting said pulleys for rotation, said supporting means being rotatable in the same direction as said pulley face. 35
16. A device for attachment to a head rail of a Venetian blind to tilt the tilt rail thereof, said device comprising a bracket for attachment to said head rail, a shaft rotatably supported on said bracket, a worm on said shaft, a plate bent to provide a gear segment plate portion to cooperate with said worm and to provide another portion for supporting said tilt rail, and means releasably engaging said plate with said bracket and supporting said plate for rotation on said bracket. 40
